WESTON M. FULTON, OF KNOXVILLE, TENNESSEE, ASSIGNOR TO THE FULTON COMPANY, OF KNOXVILLE, TENNESSEE, A CORPORATION OF MAINE.

AUTOMOBILE-HEATING SYSTEM.

1,358,947.

Specification of Letters Patent. Patented Nov. 16, 1920.

Application filed August 31, 1916. Serial No. 117,874.

To all whom it may concern:

Be it known that I, WESTON M. FULTON, a citizen of the United States of America, and a resident of Knoxville, Tennessee, have 5 invented a new and useful Improvement in Automobile-Heating Systems, which invention is fully set forth in the following specification.

This invention relates to a heating system 10 for automobiles, and it has for an object to provide a system of this type, utilizing the exhaust gases of the engine as a source of heat which shall be simple in construction, easily installed, inexpensive to manu- 15 facture, and efficient in operation.

A further object of this invention is to 20 provide a heating system of the type characterized with thermo-sensitive means for controlling the temperature of the heating 25 fluid, whereby a substantially uniform heating effect may be obtained in the automobile.

Yet another object of the invention is to 25 provide a system of this type with a thermo- sensitive control that may be adjusted to predetermine the temperature to be main- 30 tained in the automobile.

Stated broadly, the invention comprises 35 a heating means for the automobile, preferably in the form of a radiator in the body 40 of the automobile; means for utilizing the exhaust gases of the engine as a source of heat, preferably in the form of a heater through which the exhaust gases are passed and through which a fluid medium is passed 45 in heat-interchanging relation with said gases; a system including said radiator and heater for circulating said fluid medium through said heater and to and from the heating device in the automobile; and ther- 50 mosensitive means controlling the heating capacity of said last named system preferably in the form of a valve regulating ad- mission of the exhaust gases to said heater; said thermosensitive means being shown as 55 adjustable to predetermine the temperature at which said heating fluid shall be main- 60 tained.

The invention is capable of receiving a 65 variety of mechanical expressions, one of 70 which, for the purpose of illustration, has been shown on the accompanying drawing; but it is to be expressly understood that the drawing is for purposes of illustration only, and is not to be construed as a definition of

the limits of the invention, reference being 55 had to the appended claims for that purpose.

The drawing represents somewhat dia- 60 grammatically an elevation of an embodi- ment of the invention, certain parts being shown in section.

Referring in detail to the drawing, 1 re- 65 presents the usual conduit for conducting the exhaust gases from the engine to any usual form of muffler, diagrammatically indicated at 2. In the form shown, a by-pass is pro- 70 vided for the exhaust gases as by the inser- 75 tion of a Y-coupling 3 in said conduit 1. From said Y-coupling 3 extends a pipe 4 communicating through elbow 5 with con- 80 duit 6 leading into a heater, generally indi- 85 cated at 7. This heater may be of any suit- 90 able construction, the embodiment illus- 95 trated comprising a casing 8 communicating with the conduit 6 at one end and communi- 100 cating at its other end with the exhaust con- 105 duit 1 through conduit 9, elbow 10, pipe 11, and Y-coupling 12 inserted in said conduit 1. Surrounding the aforesaid casing 8 is a 110 second casing 13 through which the heating 115 fluid is passed. Said casing 8 is shown as 120 intersected by a plurality of pipes 14 where- 125 by the heating fluid may circulate through 130 said pipes, as well as around the exterior of 135 the casing 8. Leading from the casing 13 140 is a conduit 14 for conducting the heating 145 fluid to one or more heating devices of any 150 suitable construction in the automobile, two 155 such heating devices in the form of radi- 160 ators 15 being illustrated as positioned under 165 the seats of the automobile. It is to be 170 expressly understood, however, that any de- 175 sired number or kind of heating device may 180 be employed, and they may be positioned 185 wherever desired, the location under the 190 seats being convenient but not essential to 195 this invention. From the heating device or 200 devices 15 the heating fluid is returned to 205 the heater 7 through conduit or conduits 16.

In accordance with the present invention, 210 thermosensitive means are provided for 215 controlling the heating capacity of the sys- 220 tem including said heater, radiators and 225 communicating conduits, such control being 230 obtained preferably by the provision of 235 valve means for regulating the admission of 240 the exhaust gases to the heater, such thermo- 245 sensitive means being preferably controlled 250 by the temperature of the heating fluid flow-

- ing through the system. In the embodiment illustrated, a second by-pass is provided between the inlet for the exhaust gases to the heater and the main exhaust conduit 1, as 5 by the use of a T-coupling 17 in the conduit 6, a second T-coupling 18 in the conduit 1, and a connecting pipe 19. Valve means are provided for controlling the flow of the exhaust gases through the heater and the pipe 19. While any suitable form of valve means 10 may be employed, the embodiment illustrated comprises a butter-fly valve 20 pivoted within the T-coupling 17, and of such construction and mounting that at one extremity of its range of movement it entirely 15 closes admission to the pipe 19, while at the other extremity of its range of movement it entirely closes admission to the casing 8 of the heater 7. Said valve 20 is shown as pivoted with an operating crank-arm 21 connected by link 22 with a lever 23 pivoted on the casing of a thermosensitive means 24 extending into heat-interchanging relation 20 with the heating fluid. In the form shown 25 the casing 13 is provided with an extension 25 for receiving the thermosensitive means 24. While any suitable form of thermosensitive means may be employed, the illustrated embodiment comprises a thermostat 30 of the general type disclosed in my Patent No. 1,153,214, granted September 14, 1915. Means are also preferably provided to 35 predetermine the minimum temperature at which the thermosensitive means assumes control of the valve 20. In the form shown, a coil spring 27 is connected at one end to the lever 23 and at its opposite end to a block 26 received upon the threaded end of an adjusting screw 28, which is mounted in 40 a bracket 29 desirably constituted by an extension of the casing 13. Block 26 may be provided with a pointer 30 for coöperation with a scale 31 mounted in any convenient manner.
- 45 For controlling the admission of the exhaust gases to the by-pass leading through the heater, a valve 32 may be mounted in the Y-coupling 3 and provided with a manually operable member 33. This valve at one extremity of its range of movement closes the main exhaust conduit 1, and at the other extremity of its range of movement closes admission to the pipe 4 of the aforesaid by-pass.
- 50 An expansion chamber is preferably connected into the system through which the heating fluid circulates. While any one of a variety of forms of expansion chamber may be employed, the preferred embodiment comprises an expandible and collapsible corrugated vessel 34 communicating with any suitable part of said system, as with the conduit 14, by a pipe 35, and having its movable end wall engaged by a coil spring 60 36. The opposite end of said spring is en-

gaged by an adjusting screw 37 in screw-threaded engagement with a frame 38, shown as surrounding the vessel and spring and supported on the pipe 35.

When it is desired to utilize the exhaust 70 gases of the engine as a heating medium, valve 32 is moved to the position shown on the drawing, closing the main exhaust conduit 1 and diverting the exhaust gases through the by-pass constituted by pipe 4, 75 conduit 6, casing 8, conduit 9, and pipe 11, from which the gases return to the conduit 1. In their course through the casing 8, they entirely surround the pipes 14 and give up their heat to the heating fluid passing 80 through these pipes, and also give up heat through the walls of the casing 8 to the fluid surrounding this casing. The fluid in the casing 13 becoming heated, a circulation is set up through the system comprising the 85 conduit 14, radiators 15, and conduit 16. With the rise of temperature of the heating fluid the thermosensitive means tends to operate lever 23. Until this tendency is sufficiently great to overcome the opposition of 90 spring 26, lever 23 does not respond to this tendency of the thermosensitive means. When the initial temperature at which the thermosensitive means is to assume control of the valve 20 has been reached, lever 23 95 will operate valve 20 through link 22 and crank-arm 21 to admit the exhaust gases to the pipe 19, proportionately decreasing admission of the exhaust gases to the heater 7. A continued rise in temperature of the heating fluid will eventually cause the valve 20 to assume the dotted line position shown on the drawing, closing admission of the gases to the heater and entirely diverting them through the secondary by-pass comprising 100 the pipe 19. The thermostat will normally maintain the valve 20 in a position to so proportion the flow of exhaust gases through the heater 7 and the pipe 19 as to maintain the heating fluid in the system at a substantially uniform temperature as predetermined by the adjustment of the spring 27. As the fluid in the system expands on rise of temperature, the expandible and collapsible vessel 34 expands against the adjustable 105 tension of the spring 36.

While the illustrated embodiment has been described with considerable particularity, it is to be expressly understood that the invention is not to be restricted to the form shown 110 on the drawing, as other mechanical expressions will readily suggest themselves to those skilled in the art, while certain features thereof are capable of use without other features thereof. The limits of the 115 invention are to be determined by reference to the claims appended hereto.

What is claimed is:—

1. A heating system for automobiles comprising a radiator constituting a heating 120

- means for the automobile, a heater for a fluid medium through which the exhaust gases of the engine are passed, a system including said radiator and heater for circulating said fluid medium to and from said radiator and through said heater in heat-interchanging relation with said exhaust gases, and thermosensitive means for regulating the flow of exhaust gases through 5 said heater.
2. A heating system for automobiles comprising a radiator constituting a heating means for the automobile, a heater for a fluid medium through which the exhaust 10 gases of the engine are passed, a system including said radiator and heater for circulating said fluid medium to and from said radiator and through said heater in heat-interchanging relation with said exhaust 15 gases, and means controlled by the temperature of said fluid medium for regulating the flow of exhaust gases through said heater.
3. A heating system for automobiles comprising a radiator constituting a heating 20 means for the automobile, a heater for a fluid medium through which the exhaust gases of the engine are passed, a system including said radiator and heater for circulating said fluid medium to and from said 25 radiator and through said heater in heat-interchanging relation with said exhaust 30 gases, means controlling the heating capacity of said last-named system, and thermosensitive means controlling said last-named 35 means.
4. A heating system for automobiles comprising a radiator constituting a heating means for the automobile, means for conducting a heating fluid to and from said 40 radiator, a heater for said fluid through which the exhaust gases of the engine are passed, means controlling the heating capacity of said last-named system, and means controlled by the temperature of said fluid 45 for controlling said last-named means.
5. A heating system for automobiles comprising, in combination with the conduit for the exhaust gases of the engine, a by-pass for the exhaust gases, a fluid-heater in 50 said by-pass, means for conducting the heated fluid to and from said heater through a heating device in the automobile, and thermosensitive means for controlling the flow of exhaust gases through said by-pass.
6. A heating system for automobiles comprising, in combination with the conduit for the exhaust gases of the engine, a by-pass for the exhaust gases, a fluid-heater in said 55 by-pass, means for conducting the heated fluid to and from said heater through a heating device in the automobile, and means controlled by the temperature of said fluid for controlling the flow of exhaust gases through said by-pass.
7. In a heating system for automobiles, in 60 combination with the conduit for the exhaust gases of the engine, a by-pass for said gases, a fluid-heater in said by-pass, a radiator in the body of the car, means for conducting the heated fluid to and from said radiator and heater, a valve controlling the flow of exhaust gases through said heater, and thermosensitive means controlling said valve. 70
8. In a heating system for automobiles, in combination with the conduit for the exhaust gases of the engine, a by-pass for said gases, a fluid-heater in said by-pass, a radiator in the body of the car, means for conducting the heated fluid to and from said 75 radiator and heater, a valve controlling the flow of exhaust gases through said heater, and means controlled by the temperature of said fluid for controlling said valve. 80
9. A heating system for automobiles comprising, in combination with the conduit for the exhaust gases of the engine, a by-pass for the exhaust gases, a fluid-heater in said by-pass, a second by-pass between the inlet of said heater and said exhaust conduit, and valve means regulating the admission of exhaust gases to said heater and second by-pass. 85
10. A heating system for automobiles comprising, in combination with the conduit for the exhaust gases of the engine, a by-pass for the exhaust gases, a fluid-heater in said by-pass, a second by-pass between the inlet of said heater and said exhaust conduit, valve means regulating the admission 90 of exhaust gases to said heater and second by-pass, and thermosensitive means controlling said valve means. 95
11. A heating system for automobiles comprising, in combination with the conduit for the exhaust gases of the engine, a by-pass for the exhaust gases, a fluid-heater in said by-pass, a second by-pass between the inlet of said heater and said exhaust conduit, valve means regulating the admission 100 of exhaust gases to said heater and second by-pass, and means controlled by the temperature of the heated fluid for controlling said valve means. 105
12. A heating system for automobiles comprising, in combination with the conduit for the exhaust gases of the engine, a by-pass for the exhaust gases, a fluid-heater in said by-pass, a second by-pass between the inlet of said heater and said exhaust conduit, valve means regulating the admission 110 of exhaust gases to said heater and second by-pass, and a valve controlling said first-named by-pass. 115
13. A heating system for automobiles comprising a radiator constituting a heating means for the automobile, a heater for a fluid medium and through which the exhaust gases of the engine are conducted, a system including said radiator and heater 120
- 130

for circulating said fluid medium to and from said radiator and through said heater in heat-interchanging relation with said exhaust gases, a valve controlling admission 5 of said gases to said heater, thermosensitive means controlling said valve, and means to predetermine the temperature at which said thermosensitive means operates said valve.

14. A heating system for automobiles 10 comprising a radiator constituting a heating means for the automobile, a heater for a fluid medium, a by-pass including said heater and through which the exhaust gases of the engine are conducted, a system including said radiator and heater for circulating said fluid member to and from said radiator and through said heater in heat-interchanging relation with said exhaust gases, a valve controlling admission of said gases to said 15 heater thermosensitive means controlling said valve, and an adjustable spring opposing actuation of said valve by said thermosensitive means.

15. A heating system for automobiles 20 comprising a radiator constituting a heating means for the automobile, a heater for a fluid medium and through which the exhaust gases of the engine are conducted, a system including said radiator and heater 25 for circulating said fluid medium to and

from said radiator and through said heater in heat-interchanging relation with said exhaust gases, thermosensitive means for controlling the heating capacity of said last-named system, and an expansion chamber 35 communicating with said last-named system and comprising an expansible and collapsible corrugated vessel.

16. A heating system for automobiles comprising a radiator constituting a heating 40 means for the automobile, a heater for a fluid medium, a by-pass including said heater and through which the exhaust gases of the engine are conducted, a system including said radiator and heater for circulating said fluid medium to and from said radiator and through said heater in heat-interchanging relation with said exhaust gases, thermosensitive means for controlling the heating capacity of said last-named system, an expansion chamber communicating with said last-named system and comprising an expansible and collapsible corrugated 45 vessel, having a movable end wall, and an adjustable spring opposing movement of said 50 end wall.

In testimony whereof I have signed this specification.

WESTON M. FULTON.
